UNITED STATES PATENT OFFICE.

STEPHAN A. BLAŽEK, OF NEW YORK, N. Y.

KEYLESS LOCK.

1,157,837.

Specification of Letters Patent.

Patented Oct. 26, 1915.

Application filed July 25, 1914. Serial No. 853,238.

To all whom it may concern:

Be it known that I, STEPHAN A. BLAŽEK, a citizen of the United States, and a resident of New York, in the county of New York and State of New York, have invented certain new and useful Improvements in Keyless Locks, of which the following is a specification.

This invention relates to improvements in locks, and particularly to that type known as permutation, in which no key is used.

The objects of the invention are, to provide a lock in which the engaging elements can be inserted and secured irrespective of the position of the mechanical elements of the lock body. Second, to provide a lock particularly adapted for traveling cases, valises, satchels and the like, which it is desired to secure in a closed position against inadvertent or unauthorized opening. Third, to provide a lock of the class described, comprised of essentially simple elements, readily operated and which afford unusual convenience and security. These and other allied objects are obtained by the novel construction and combination of parts, hereinafter described and shown in the accompanying drawings, in which:

Figure 1 is a plan view of the lock. Fig. 2 is a front elevation of the same, showing the hasp plate in engagement. Fig. 3 is a bottom plan view of the lock, the parts being shown in position for unlocking. Fig. 4 is a sectional view taken on line 4—4 of Fig. 3. Fig. 5 is a perspective view of the bolt or hasp engaging element, and, Fig. 6 is an enlarged sectional view taken on line 6—6 of Fig. 4.

The invention is comprised of a suitable casing 10 which may be formed from a single sheet of material and provided with ears or extensions 12 for convenience in securing the lock in position upon the article to which it is applied.

Upon the hinged member of the article is attached a hasp plate 15 provided with projecting hooks 16 adapted to enter openings 11 formed in the adjacent side of the lock casing and there become engaged with the sliding bolt 18 normally pressed toward one end by reason of the spring 19. This bolt 18 has an end member 20 formed integrally with it at a right angle, the extreme end of which acts as a guide within the casing 10 to maintain the bolt in proper position. The other end of the bolt 18 is

provided with an arm 21 for a similar purpose and also a central upstanding and outwardly turned projection 22 against which one end of the spring abuts, the other end 60 being held against the end wall of the casing.

The plate 23 is slidably contained adjacent to the bolt 18 and has at one end a vertical wall 24 against which the bolt member 65 20 normally abuts. This plate is provided with elongated openings 25 and 26 near each end into which extend projections 27 and 28 respectively. Also on this plate is a central raised lug 29 doubling the thickness of 70 the plate, and having at one end a projection 29', corresponding with the projection 28 on the plate immediately below; secured in the plate and lug is the stem 30' of the center knob 30 which is adapted to move 75 longitudinally in a groove 31 formed in the top of the casing 10. At each side of this center knob are other knobs 32 and 33, similar in appearance, which are provided with dials 34 and 35 on which are numerals and 80 other characters signifying the position of the disk tumblers 36 and 37 rigidly attached to the stems of these knobs immediately beneath the casing shell and in register with the mentioned openings 25 and 26 in the 85 slidable plate 23. In both of these tumblers are notches 36' and 37' suited to receive the projections 27 and 28. Also upon one or both of these knobs is a freely rotatable disk tumbler 40 similar in character to those 90 previously described but capable of turning upon the stem. At one side of each of these upper tumblers is inserted a pin 41 adapted to make contact with a carrier 42 rigidly secured to the extreme inner end of the knob 95 stem and arranged to transmit motion through contact with the pin to the outermost tumblers 40 which is arranged to be in the same horizontal plane as the lug 29. These tumblers 40 are made with indentations 40' coincident with the characters upon the index or dial connected with the knobs and adapted to receive pressure from a flat spring 43 sufficient only to prevent inadvertent turning of the same. Both the 100 bolt 18 and plate 23 are held within the casing by means of a flat plate 45 corresponding to the bottom of the casing and adapted to be secured between it and the article to which the lock is applied.

In operation, the parts being properly assembled and attached to the article to be

locked, it will be noticed that the hooks 16 on the hasp plate 15 may be entered through the openings 11 in the front wall of the lock casing, the result being to force the bolt 18 to move within the casing compressing the spring 19 sufficiently to allow this movement and that upon the hooks being entered the pressure of the spring will serve to snap the bolt back, thus locking the hooks 10 securely in engagement with it.

In order to release the hasp plate, it is necessary to manipulate the center knob which can only be done at such times as the tumblers 36, 37 and 40 are in position to 15 receive the projections 27, 28 and 29' on the movable plate 23 and lug 29.

In the case of the tumblers being rigidly attached to the knob stems, it is necessary only to turn the dial index until a pre-arranged character is in proper relation to some mark on the outer casing; but when a plurality of tumblers are used, the loose tumblers are brought into position by the carrier 42 and pin 41 and held by reason of 25 the spring tension on them, thus reversing the direction of rotation until the rigid tumblers are brought into a corresponding position which can be ascertained by the index figures on the dial secured to the knob.

30 While the foregoing describes and indicates the application of the lock, it is not desired to be constrained to the exact construction shown, as obviously both sets of tumblers may be made in either of the styles 35 shown, or both may be alike as preferred, and that there are other modifications which can be made without departing from the scope of the claims hereby appended.

Having thus described my invention, what 40 I claim as new and desire to secure by Letters Patent, is:

1. In a device of the class described, the combination with a casing, a spring actuated bolt and a sliding plate combined 45 therewith, said plate having elongated apertures, of a knob operative with said plate, tumblers in the mentioned apertures, knobs upon which said tumblers are fixed, a loose tumbler mounted on one of said knobs be-

yond said fixed tumblers and means for rotating said loose tumbler independently. 50

2. In a device of the class described, the combination with a casing, a sliding plate, a bolt having two engaging points operable closely against the interior walls of said casing, means for maintaining the bolt in a normally locking position, means combined with said plate for actuating said bolt, tumblers arranged in alinement at different points in the path of travel of said plate, 55 means for rotating said tumblers and means for operating said plate, said plate operating means being intermediate of said tumbler operating means.

3. In a device of the class described, the combination with narrow elongated casing, a plate slidably mounted therewithin, said plate having elongated openings, projections integral with said plate extending into the mentioned openings, tumblers rotatably 70 disposed in a straight line uniformly spaced and slotted to receive said projections, means for operating said tumblers, a bolt operable by said plate, said bolt being also independently movable and maintained normally in a locking position, and means intermediate of said tumbler operating means for actuating said bolt. 75

4. In a device of the class described, the combination with a casing and a hasp plate 80 having members adapted to enter within the casing, of a bolt engageable with said members, a plate slidably in said casing having a part for disengaging said bolt from said members, a raised lug on said plate, tumblers engaging with said plate, a loose tumbler engaging with the raised lug on said plate, means for operating all of said tumblers independently and means for actuating 85 said plate. 90

In testimony whereof I have signed my name to this specification in the presence of two subscribing witnesses.

STEPHAN A. BLAŽEK.
